UNITED STATES PATENT OFFICE.

ERNEST W. PITTMAN, OF WHEATON, ILLINOIS, ASSIGNOR, BY MESNE ASSIGNMENTS,
TO STANDARD GAS EQUIPMENT CORPORATION OF MARYLAND.

STOVE STRUCTURE.

Application filed May 27, 1925. Serial No. 33,274.

This invention relates to the frame structure of stoves and ranges, such as gas stoves, electric stoves, and the like, and the invention consists of certain improvements in the form and construction of the door frame; the manner of attaching the same to the stove structure; the form and construction of the stove doors; the form and construction of the hinges for mounting the doors in the door frame; and other features of construction, said improvements having in view the production of a stove structure of light, efficient, and durable form, pleasing and finished in appearance, and in which the parts will be held firmly together without danger of looseness or displacement.

In the specification to follow the invention will be described in detail, and the novel features thereof pointed out in the appended claims.

In the accompanying drawings:

Fig. 1 is a perspective view of the forward portion of a stove having the invention embodied therein.

Fig. 2 is a fragmentary view in front elevation of one side of the door frame structure and door, a portion of the door being broken away to show the hinge therefor.

Fig. 3 is a vertical sectional elevation on the line 3—3 of Fig. 2.

Fig. 4 is a view similar to Fig. 3, on an enlarged scale, showing the door in open position.

Fig. 5 is a horizontal section on an enlarged scale on the line 5—5 of Fig. 2.

Fig. 6 is a side elevation of a portion of the blank employed in forming the oven door.

Fig. 7 is an elevation of the inner side of the door formed from the blank of Fig. 6.

Fig. 8 is a vertical section through the upper portion of the door frame and door on the line 8—8 of Fig. 1.

Fig. 9 is a perspective view of the blank from which the door frame is made.

Fig. 10 is a similar view showing the blank in the first stage of its formation to produce edge flanges thereon.

Fig. 11 is a perspective view of the same, notched in its opposite edges to enable it to be bent into U form.

Fig. 12 is a perspective view of the notched blank of Fig. 11 showing the same bent longitudinally to give it a hollow tube-like form in cross section.

Fig. 13 is an inside perspective view of a portion of the longitudinally bent blank of Fig. 12.

Fig. 14 is an outside perspective view of the finished door frame, showing the notched blank of Fig. 12 bent at the points where the notches are located, to give the frame its U form.

Fig. 15 is an inside perspective view of the same.

Fig. 16 is an elevation of the blank from which the front wall of the oven door is constructed.

Fig. 16^a is a cross section through the same.

Fig. 17 is an elevation of said blank notched and shaped preparatory to bending it into form.

Fig. 17^a is a cross section through the same.

Fig. 18 is an elevation of the notched blank after being partially bent into form.

Fig. 18^a is a cross section through the same.

Fig. 19 is an elevation of the blank fully bent to form.

Fig. 20 is an elevation of the completed oven door as viewed from the inside.

Fig. 21 is a perspective view of the door with certain parts in section and other parts broken away.

Referring to the drawings:

The oven structure 1, comprising the two side walls, the top wall, and the rear wall (not shown), is supported on a suitable base 2, the said walls enclosing a heating chamber which is divided by a horizontal partition or oven floor *a*, into an oven chamber at the top and a broiler chamber beneath, which chambers are adapted to be closed at their front by doors 9, only one of which, that for the oven chamber, is shown as mounted in a door frame 3 fixed to the front of the oven walls.

The door frame 3 is of inverted U form in general contour, and comprises the vertical side bars 5 and 6, and the horizontal top cross bar 4 connected to the upper ends of the side bars, the said bars extending along and connected to the front edges of the side walls of the oven structure, and the cross bar extending along and being connected to the front edge of the top wall of the same. The frame thus constitutes a marginal edging for the front of the oven walls,

of a form and construction which will serve as a support and mounting for the oven doors.

The door frame 3 is made preferably from a single piece of sheet metal which is shaped and bent, as will be presently described in detail, to give it a hollow or shell-like form in cross section and is formed with a front wall 6^a extending linearly throughout the extent of the frame, an outer side wall 6^b extending rearwardly from the outer edge of the front wall at right angles thereto, a rear wall 6^c extending inwardly from the rear edge of the side wall and disposed some distance in rear of the front wall, by means of which rear wall the frame is fastened to the oven structure, an inner side wall 6^d extending rearwardly from the inner edge of the front wall, and an angular flange 3^e connected to the edge of the inner side wall and constituting a ledge or jamb for the oven door to close against. The door frame thus constructed and constituted, forms, due to the bending of the metal at the junction of the several walls or flanges, a stiff and light unitary structure, and lends itself to the best advantage in giving support to the oven doors, and for attachment by bolts or other suitable fastening means, to the walls of the oven structure without the said fastening means being visible.

This will be best understood by reference to Fig. 5 where it will be seen that the rear wall 6^c of the frame structure consists of an inclined portion 3^f extending inwardly from the inner edge of the side wall, and an angularly related terminal portion 3^g, which are seated flatly and abut against the front face of a flange extending inwardly from the front edges of the oven walls and consisting of an inclined portion 1^b and an angularly related terminal portion 1^c, which abutting parts are firmly bolted together by fastening bolts 8 extending through the terminal portions 1^b and 3^g at suitable intervals, and the terminal portion 1^c being formed with a forwardly turned lip 1^d against which the inner edge of the terminal portion 3^g abuts, and by which, relative motion or slip of the parts will be effectually prevented. The angularly related portions of the rear wall of the door frame thus interlock with the angularly related portions of the flange on the oven walls, whereby the proper location of the door frame on the oven structure in the assembly of the parts is facilitated and assured, and the relative motion or looseness of the parts of the assembled structure prevented.

While by this method of attaching the door frame to the oven walls, a very stable, firm, and close connection of the parts is secured, the attaching means are wholly enclosed within the walls and therefore entirely concealed from view, so that the structure

will present on its exterior a smooth, finished, and neat appearance. A door frame possessing the above described structural features may be formed in any appropriate and suitable way, but I preferably construct the same in the following manner.

A sheet metal blank is provided of the form shown in Fig. 9, and by suitable tools or dies the edges of the blank are bent along longitudinal lines so as to form thereon the angular flanges 3^f 3^g and 3^h as shown in Fig. 10, the flanges 3^f 3^g to eventually form the rear wall of the finished frame, and the flange 3^h to form the inner side wall or jamb ledge of the finished frame. As shown in Fig. 11, the flanged blank is next notched in opposite edges as at 3ⁱ and 3^j through the flanges at two points in the length of the blank, to permit the latter to be subsequently bent to give the frame its final inverted U form. Next the notched flanged blank is bent on a longitudinal line midway between its flanged edges, so as to dispose the bent portions at right angles to each other as shown in Fig. 12, whereby the structure is given the hollow or shell-like form in cross section which the finished frame possesses as before described. The hollow notched structure of Fig. 12 is now given the final inverted U form of the finished frame by bending the end portions inwardly towards each other, at the apices of the notches, and disposing the bent portions parallel to each other to constitute the side bars 5 and 6, (see Figs. 14 and 15), before alluded to. In this action the diagonal edges of the several notches are caused to abut, and these edges are welded or otherwise united to preserve and maintain the final form of the frame.

As shown in Figs. 1, 2 and 3, a horizontal center bar 7 is set in between the side bars of the door frame at a point about midway of the height of the same, and firmly fastened thereto in any suitable manner, as for instance by welding. This bar in the present instance is made from a single piece of sheet metal which is bent on longitudinal lines so as to present a front vertical flat face or wall 7^a, an upper horizontal ledge 7^b, a vertical flange 7^c extending upwardly from the rear edge of the ledge, and a lower vertical flange 7^d at the lower edge of the bar, the said bar being fastened in place preferably by welding the ends of the front wall 7^a to the inner side walls of the U-frame as shown at 7^e. This center bar serves the three-fold purpose of affording a support for the forward end of the horizontal partition or oven floor a before alluded to, which is suitably fastened at its front edge to the upper edge of the flange 7^c; a support constituted by the ledge 7^b and flange 7^c for the door 9 of the oven chamber; and an abutment constituted by the flange 7^d for the upper edge of the door

of the broiler chamber as will more fully appear later on. The doors 9, of which there will be two, one for the oven chamber, and one for the broiler chamber one only being shown, are in the present instance made of sheet metal and are of box like or hollow form consisting each, as shown in Fig. 21, of a main body portion or front wall 9^a having side and end walls 9^d provided with inturned 5 lips 9^e, and a back plate 9^f welded or otherwise fastened to the inturned lips and constituting the rear wall of the door. In making up this door structure a sheet metal blank of the form shown in Fig. 16 is provided, having thrown up at its center a panel 9^a for strengthening it. The corners at the top of the blank are cut away and notched as shown at 9^e and 9^b, and the lower corners are cut away and recessed as at 9¹ and 9². 10 The marginal portions of the blank are now bent rearwardly to form the end and side walls 9^d, and the edges of the walls are bent inwardly to form the lips 9^e. As a result of these bending actions, the edges of the 15 notches are brought together and they are united by welding to preserve the final form of the structure; the form of the cut away portions and notches 9¹ and 9² being such that the lower ends of the side walls will 20 terminate a short distance above the lower wall 9^d of the door and slots 9^g will be formed in the inturned flanges 9^e adjacent their lower ends as clearly shown in Figs. 4 and 21. 25 The hinged support of the door 9 by the center bar 7 is effected through the medium of two rocker plates or hinges 10, consisting each of a stem 10^a and an elliptical rocker head 10^b on the lower end of the stem, the 30 said stems being seated flatly against the inner sides of the side walls of the door at their lower ends, to which they are welded, and the elliptical heads projecting downwardly beyond the lower ends of said side 35 walls and beyond the lower wall of the door so as to seat on the ledge 7^a of the center bar as shown in Figs. 2 and 4. As a result of 40 this construction and arrangement of the parts, the door may be swung up and down to closed and open positions respectively, and in such movements the curved edges of the 45 rocker heads will roll or turn on the ledge 7^a and in contact with the flange 7^b, the heads being held on the ledge and against 50 the flange by means of curved arms 10^b extending rearwardly from the stems 10^a of the rocker plates and sliding through vertical 55 slots 3^d formed in the angular flanges 3^e of the door frame. The ends of said arms terminate in hooks 10^d, adapted, when the door 60 is swung down to a horizontal open position, to engage with wear plates 10^e fixed to the sides of the door frame, and thereby limit the downward movement of the door and 65 hold the same in a horizontal open position.

The curvature of the inner edges 10^c of the arms 10^b is such that these edges will contact with the lower walls of the slots 3^d in the opening and closing movements of the door, and by such contact, and due to the 70 curved path in which the arms move, the rocker heads will be held confined on the ledge and against the flange 7^b. The major axis of the elliptical heads extends at right angles to the plane of the door, so that the 75 curved edges of the heads on such major axis are engaged with the ledge in the final stage of the opening movement of the door, and by such engagement, the door is lifted bodily slightly and brought in its full open position to a level with the floor *a* of the oven chamber, thereby enabling cooking utensils in the oven to be drawn outwardly therefrom without obstruction and be received 80 directly and supported by the oven door. 85

On reference to Fig. 4 it will be seen that as the door is swung upward from its horizontal open position to a closed position, due to the engagement of the curved edges on the minor axis of the rocker heads with the ledge, the inner curved edges of the arms 10^b will come into engagement with the lower walls of the slots 3^d, and in the continued closing movement of the door, these edges 90 will maintain engagement with said walls and thereby hold the rocker arms on the supporting ledge. 95

In the closed position of the door as shown in Fig. 3, the lower end wall 9^d thereof will be sustained close down to the upper surface of the ledge 7^a of the center bar, the rear face of the door at its lower end will lie flatly and closely against the flange 7^b of the center bar, while the remaining marginal surface at the rear face of the door will bear flatly and closely against the angular flange 3^c projecting inwardly from the inner side wall of the door frame; whereby the oven chamber will be effectually sealed by the door against the entrance of cold air and the escape of hot air. 100 105 110

It will be observed from Fig. 1 that by reason of the form and construction of the hinge members and the manner of attaching and mounting them, they are practically hidden from view, both when the door is in closed position and in open position, the only visible portion of the hinges being the very limited areas of the elliptical heads where they project beyond the front wall of the 115 door. 120

In order to counterbalance the weight of the door in its opening and closing movements and assist in the closing movement, counterbalancing tension springs *b* are employed as shown in Figs. 3 and 4, which springs are attached at their lower ends to brackets *c* on the door frame and at their upper ends to the hooks 10^d of the rocker plates. 125 130

While in the foregoing description and accompanying drawings the invention is disclosed as embodied in a certain detailed form and construction of the parts, it will be understood that these details may be variously changed and modified without departing from the invention; and it will be further understood that the invention is not limited to any particular form or construction of the parts except in so far as such limitations are specified in the claims.

I claim:

1. A door frame for a stove structure, said frame being formed from a single piece of sheet metal and comprising two side bars and an end connecting bar, said bars being hollow in cross section and comprising a front wall, inner and outer side walls extending rearwardly from the edges respectively of the front wall, and a rear wall extending inwardly from the outer side wall.

2. A door frame for a stove structure, said frame being formed from a single piece of sheet metal and comprising two side bars and an end connecting bar, said bars being hollow in cross section and comprising a front wall, inner and outer side walls extending rearwardly from the edges respectively of the front wall, and a rear wall extending inwardly from the outer side wall, the said walls being formed with opposing notches at two points in their length, and bent at the apices of the notches to give the frame a U shape, and the edges of the notches being united to preserve said shape.

3. A door frame for a stove structure, said frame being formed from a single piece of sheet metal bent along transverse lines to form two side bars, and an end connecting bar, and said bars being bent along longitudinal lines to form a front wall, inner and outer side walls extending rearwardly from the edges respectively of the front wall, and a rear wall extending inwardly from the outer side wall.

4. A stove structure comprising side walls enclosing a heating chamber and formed at their front with inwardly extending marginal flanges, and a door frame formed with side walls and with rear walls extending inwardly from the rear edges of said side walls and seated against and fastened to the said marginal flanges.

5. A stove structure comprising side walls enclosing a heating chamber and formed at their front with an inwardly extending marginal flange, and a sheet metal door frame formed with two side bars and an end connecting bar, said bars being hollow in cross section and comprising a front wall, inner and outer side walls, and a rear wall extending inwardly from the rear edge of the outer side wall, said rear wall being seated against and fastened to said marginal flange.

6. A stove frame structure comprising side

walls enclosing a heating chamber and formed at their front with inwardly extending marginal flanges consisting of angularly related portions, and a door frame applied to the front of said walls and formed with side walls, and rear walls extending inwardly from the rear edges of the side walls and consisting of angularly related portions seated against and secured to the angularly related portions of the marginal flanges.

7. A stove frame structure comprising side walls enclosing a heating chamber and formed at their front with an inwardly extending marginal flange having a forwardly extending terminal lip, and a door frame applied to the front of said walls and provided with an inwardly extending flange seated against and fastened to said marginal flange and having its edge abutting said lip.

8. In a stove structure, the combination of walls enclosing a heating chamber, a door frame applied to the front of said walls, a door supporting surface at the bottom of the heating chamber, a door adapted to seat against the door frame to close said chamber, and means for hingedly supporting the door to permit it to be opened to a horizontal position, said means acting to lift the door bodily in its movement to a horizontal open position to dispose its inner side on a level with the bottom of the heating chamber.

9. In a stove structure, the combination of walls enclosing a heating chamber, a door frame applied to the front of said walls, a door supporting surface at the bottom of the heating chamber, a door adapted to seat against the frame to close the heating chamber, heads fixed to the lower end of the door and adapted to be supported by and rock on said supporting surface, and means independent of the said supporting surface for holding the same on said supporting surface in all of the positions of the door.

10. In a stove structure, the combination of walls enclosing a heating chamber, a door frame applied to the front of said walls, a horizontal bar fixed at its ends to the sides of the door frame, a horizontal partition extending from said bar rearwardly within the heating chamber and constituting the bottom of the upper chamber, a door adapted to seat against the door frame to close the upper chamber, and means for hingedly supporting the door on said bar to permit it to be opened to a horizontal position, said means acting to lift the door bodily in its movement to a horizontal position, to dispose the inner side of the same on a level with the bottom of the heating chamber.

11. In a stove structure, the combination of walls enclosing a heating chamber, a door frame applied to the front of said walls, a door supporting surface supported at the bottom of the heating chamber, a door

- adapted to seat against said frame to close the chamber, elliptical heads fixed to the lower end of the door and adapted to be supported by and rock on said supporting 5 surface to hingedly support the door, the major axis of said heads extending transversely of the plane of the door; whereby when the door is opened to a horizontal position it will be lifted bodily and its inner 10 side disposed on a level with the bottom of the heating chamber.
12. In a stove structure, the combination of walls enclosing a heating chamber, a door frame applied to the front of said walls, a 15 door supporting surface at the bottom of the heating chamber, a door adapted to seat against said frame to close the heating chamber, heads fixed to the bottom of the door and adapted to be supported by and 20 rock on said supporting surface to hingedly support the door, and arms fixed to the door and extending rearwardly therefrom and cooperating with the door frame in holding the rocker heads on the supporting surface.
- 25 13. In a stove structure, the combination of walls enclosing a heating chamber, a door frame applied to the front of said walls, a door supporting surface at the bottom of the heating chamber, a door adapted 30 to seat against said frame to close the heating chamber, heads fixed to the bottom of the door and adapted to be supported by and rock on said supporting surface to hingedly support the door, and arms fixed to 35 the door and extending rearwardly therefrom through slots in the door frame and cooperating with said door frame in holding the rocker arms on the supporting surface.
- 40 14. In a stove structure, the combination of walls enclosing a heating chamber, a door frame applied to the front of said walls, a door supporting surface at the bottom of the heating chamber, a door adapted to seat 45 against said frame to close the heating chamber, heads fixed to the bottom of the door and adapted to be supported by and rock on said supporting surface to hingedly support the door, and arms fixed to the door and extending rearwardly therefrom, said arms being 50 provided with means for limiting the opening movement of the door.
15. In a stove structure, the combination of walls enclosing a heating chamber, a door 55 frame applied to the front of said walls, a door supporting surface at the bottom of the heating chamber, a door adapted to seat against said frame to close the heating chamber, heads fixed to the bottom of the door 60 and adapted to be supported by and rock on said supporting surface to hingedly support the door, arms fixed to the door and extending rearwardly therefrom and cooperating with the door frame in holding the rocker 65 heads on the supporting surface, and springs acting on said arms to counterbalance the weight of the door and assist in the closing movement.
16. In a stove structure, the combination of walls enclosing a heating chamber, a door 70 frame applied to the front of said walls and formed in its sides with slots, a door supporting surface at the bottom of the heating chamber, a door adapted to seat against said frame to close the heating chamber, heads 75 fixed to the lower end of the door and adapted to be supported by and rock on said supporting surface to hingedly support the door, and arms fixed to said door and extending rearwardly through the slots in the 80 door frame, the lower edges of said arms being curved and adapted by engagement with the lower walls of the slots to hold the heads on the supporting surface.
17. In a stove structure, the combination of walls enclosing a heating chamber, a door 85 frame applied to the front of said walls and formed in its sides with slots, a door supporting surface at the bottom of the heating chamber, a door adapted to seat against said frame to close the heating chamber, elliptical heads fixed to the lower end of the door and adapted to be supported by and rock on said supporting surface to hingedly support the door, the major axis of said heads extending 90 at right angles to the plane of the door, and arms fixed to said door and extending rearwardly through the slots in the door frame, the lower edges of said arms being curved and adapted by engagement with the lower 95 walls of the slots to hold the heads on the supporting surface.
18. In a stove structure, the combination of walls enclosing a heating chamber, a door 100 frame applied to the front of said walls, a door supporting surface at the bottom of the heating chamber, a door adapted to seat against said frame to close the heating chamber, heads fixed to the lower end of the door and adapted to be supported by and rock on said supporting surface to hingedly support the door, arms fixed to the door and extending rearwardly therefrom and cooperating with the door frame in holding the rocker 105 heads on the supporting surface, and hooks 110 on the ends of the arms adapted by engagement with the door frame to limit the opening movement of the door.
19. In a stove structure, the combination of walls enclosing a heating chamber, a door 115 frame applied to the front of said walls, a horizontal bar fixed at its ends to the sides of the door frame and formed with a horizontal supporting ledge and a vertical abutting surface at the rear edge of the ledge, a door adapted to seat against said frame to close the oven chamber, rounded heads fixed to the lower end of the door and supported by and rockable on said ledge and engaging 120 said abutting surface, and means independ- 125
- 130

ent of the heads to hold them on the ledge and in engagement with the abutting surface.

20. A stove door comprising a front rectangular body portion or wall, a marginal flange extending rearwardly from the edges of said body portion at right angles to the plane thereof, and constituting the side and the end walls of the door, a marginal lip extending inwardly from the edge of the flange and disposed some distance in rear of the body portion to leave a space between the two, and a plate fastened to said lip and constituting the rear wall of the door; whereby a hollow door structure is formed with flat extended side and end walls.

21. A stove door comprising a front rectangular body portion or wall, a marginal flange extending rearwardly from the edges

of said body portion at right angles to the plane thereof and constituting the side and the end walls of the door, a marginal lip extending inwardly from the edge of the flange and disposed some distance in rear of the body portion to leave a space between the two, a plate fastened to said lip and constituting the rear wall of the door, the lower ends of the side walls terminating some distance above the lower end wall, and plates seated against and fastened to the inner sides of the side walls and provided at their lower ends with rocker heads projecting below the lower end wall, for hingedly supporting the door.

In witness whereof, I have hereunto set my hand and affixed my seal this 21st day of May, 1925.

ERNEST W. PITTMAN. [L.S.]
